TRANSPARENCY STORAGE AND CARRYING CASE

Hiram L. Mills, Prairie Village, Kans.

Application July 3, 1956, Serial No. 42,132

Term of patent 14 years

(Cl. D87—5)

Fig. 1.

Fig. 2.

Fig. 3.

Fig. 1 is a perspective view of a transparency storage and carrying case embodying my new design, one of the covers being shown in partly open condition;

Fig. 2 is an elevational view of same in closed condition, showing the side opposite the hinge side in Fig. 1; and

Fig. 3 is an elevational view taken looking toward the left in Fig. 2, the opposite side having substantially the same appearance.

I claim:

The ornamental design for a transparency storage and carrying case, as shown and described.
